ATTORNEY

UNITED STATES PATENT OFFICE.

FRANK F. AMBROSE, OF LOS ANGELES, CALIFORNIA, ASSIGNOR TO UNION STEAM PUMP COMPANY, OF BATTLE CREEK, MICHIGAN, A CORPORATION.

ROTARY PUMP.

1,407,620.

Specification of Letters Patent. Patented Feb. 21, 1922.

Application filed April 29, 1918. Serial No. 231,403.

To all whom it may concern:

Be it known that I, FRANK F. AMBROSE, a citizen of the United States, residing at the city of Los Angeles, county of Los Angeles, State of California, have invented new and useful Improvements in Rotary Pumps, of which the following is a specification.

My invention relates to that class of rotary pumps in which piston blades are operated by a rotor in which they reciprocate, and the object thereof is to prevent wear on the casing of the pumping chamber and wear on the piston blades. A further object is to construct a pump of few parts which can be replaced when worn, and wherein the internal parts of the pump may be inspected by the removal of either end of the casing of the pumping chamber. A further object is to provide a pump in which the internal wearing parts may be oiled.

In the drawings forming a part of this application:

Fig. 1 is an end elevation of my improved pump with one of the heads removed and the hub thereof in section, with parts broken away.

Fig. 2 is a longitudinal elevation with parts in section and parts broken.

Referring to the drawings 5 is the body of the outer casing of the pumping chamber and has secured thereto legs 6 by means of which it is secured to its support when installed. This casing is circular both internally and externally, except at the induction port 7 and the eduction port 8, which ports are of usual construction. The ends of body 5 are closed by plates 9 and 10 of identical construction which are removably connected to the body in the usual manner, and only one plate will be described in detail. Plate 9 has a hub 11 projecting from its inner face. The periphery of this hub is circular and the longitudinal center of the hub is about three-sixty-fourths of an inch distant from the longitudinal center of body 5. The hub is eccentrically bored for the reception of the operating shaft 12 and is provided with a longitudinal oiling channel 13 which is crossed by radial channels 14 which terminate at the surface of the hub. On the outer surface of plate 9 is a boss 15 that surrounds shaft 12. In boss 15 is a gland 16 having an oiling channel 17 to which oil is supplied in any suitable manner. Chan-

nel 17 opens at its inner end to shaft 12. A channel in head 9 connects with channel 13 in the hub and oil is supplied thereto in any suitable manner. A tubular rotor is rigidly secured to shaft 12 by its hub 19. This rotor carries the piston blades which reciprocate in the rotor as it revolves. The outer portions 20 of the piston blades are identical in construction and are secured to yokes 21, of identical construction, by screws 22. As shown in the drawings these blades are arranged in pairs which work at right angles to each other, and the outer portions of each pair of blades are carried by two yokes one of which is secured to the outer portions of the blades at one end, and the other yoke is secured near the other end and just within the end yoke of the other pair. This manner of connecting the yokes to the outer portions of the blades locks the ends of each pair together at one end and nearly at the other end thereby keeping their outer edges absolutely parallel at all times as the wear comes on the inner sides of the yokes which are of the same size and are protected by wearing plates 23. These wearing plates are U-shaped and are tempered to withstand wear. A spring washer may be used between plates 23 and the yokes, to take up possible wear. Hubs 11 are protected by annular sleeves 25 of tempered steel in which are ports 26 which register with channels 14. It will be observed that there are as many of these sleeves as there are yokes, and that the yokes have a rolling contact therewith, and that the sleeves are revoluble on the hubs. These movements reduce friction and wear and when the parts wear, new sleeves may be substituted which will take up such wear, and the pump is thereby restored to its primary efficiency. Shaft 12 is operated by any suitable means.

By this construction it will be observed that all the wearing surfaces are formed of hardened removable parts which are kept oiled at all times. By making the ends of the pumping chamber removable repairs can be made to the interior parts by taking off either end, and either end of the pump can be placed against a wall or other immovable structure without preventing access to the interior of the pump. The blades and yokes are so constructed and operated that there is a thin skin of water between the blades

and the inner surface of the pumping chamber at all times, thereby preventing wear on the blades, from which it will be seen that the blades do not fit the casing tightly 5 at all points, and at certain points the amount of water between the edges of the blades and the casing is greater than at other points, such increase being where no loss of efficiency is incurred thereby.

10 Having described my invention, I claim:

1. A rotary pump comprising a casing having removable ends, said ends having internally projecting hubs, said hubs being slightly eccentric; wearing sleeves on 15 said hubs; a shaft eccentrically disposed through said hubs; a hollow rotor secured to said shaft; a plurality of blades arranged in pairs operated by said rotor, the blades of each pair being locked together at and 20 near the ends thereof by yokes, removable

wearing plates secured to said yokes and contacting with the sleeves on the hubs.

2. A rotary pump comprising a casing having removable ends, said ends having internally projecting hubs, said hubs being 25 slightly eccentric; a shaft disposed eccentrically through said hubs; a hollow rotor secured to said shaft; a plurality of blades arranged in pairs operated by said rotor, the blades of each pair being locked together 30 at and near the ends thereof by yokes, said yokes contacting with said hubs to cause the reciprocation of the blades in the rotor, said hubs having channels therein adapted to apply oil between said yokes and hubs. 35

In witness that I claim the foregoing I have hereunto subscribed my name this 22nd day of April 1918.

FRANK F. AMBROSE.
